(57) **CLAIM**

The ornamental design for a cup, as shown and described.

DESCRIPTION

The subject matter of this application relates to the subject matter of U.S. patent application No. 29/199,673, filed Feb. 17, 2004.

FIG. 1 is a perspective view of a cup showing my new design.

FIG. 2 is a side elevational view thereof, all sides being the same.

FIG. 3 is a top plan view of the cup of FIG. 1; and, FIG. 4 is a bottom plan view of the cup of FIG. 1.
